AUTOMOBILE RADIATOR

Stanislaus Przyborowski, Buffalo, N. Y., assignor
to Fedders Manufacturing Company, Inc.,
Buffalo, N. Y.

Application December 24, 1934, Serial No. 758,875

4 Claims. (Cl. 257—125)

This invention relates to automobile radiators, and it has particular reference to a radiator core of the cellular type, which, while light in weight, is durable and resistant to shearing and other stresses set up under conditions of use.

In the manufacture of cellular cores for automobile radiators, it has heretofore been customary to assemble a number of deformed or corrugated strips of metal to provide alternate passages for the flow of water and transverse passages for the flow of air, whereby the cooling liquid for the engine could be cooled by air flowing through the core. The upper and lower, or opposed sides, of such a core, at the open ends of the water passages, have been capped or closed by upper and lower water tanks, so that water could circulate from the engine, to one tank, through the core and into the opposite tank, and thence back to the engine. As such structures are well known, it is deemed unnecessary here to indulge in further description.

The efficiency of such a core is customarily evaluated in terms of weight of metal employed, and, to the end that the core shall be regarded as efficient by such standard, it is obvious that light or thin sheet stock is indicated. At the same time, however, there has heretofore been a limit to the thinness of the ribbons used in the core assembly, and one factor determining such thinness has been the extent of vibratory forces or shocks to which the radiator is subjected in service. In this connection, it may be added that, in recent years, there has been a trend toward more powerful engines, capable of producing higher speeds, and concurrently even more intense shocks to the radiator.

To the end that these increased destructive forces may be met without increasing the weight of the core disproportionately, and to the end that economies in manufacture and suitable efficiencies may be obtained with the use of light weight metal, the present invention contemplates the provision of means included in the radiator assembly, whereby the road shocks may be absorbed and the radiator protected. In providing such invention, it may also be noted that I have determined that such shocks are usually concentrated at the corners of the radiator core, tending to tear the light metal ribbons, and hence, in the present invention, it is proposed to meet such forces at the point of their maximum intensity and application.

A typical embodiment of the invention is illustrated in the accompanying drawing, wherefore in:

Fig. 1 is an elevation of a radiator core and tank assembly incorporating the principles of the invention;

Fig. 2 is a fragmentary perspective view of an upper corner of a cellular core, also showing the invention; and,

Fig. 3 is a section on the line 3—3 of Fig. 2.

As shown in the drawing, the radiator is composed of a fabricated core 10 and upper and lower tanks 11 and 12 respectively. The upper tank 10 is formed with a marginal flange 13 which is soldered to the adjacent face of the core 10, and the lower tank is provided with a flange 14 which is similarly secured to the lower face of the core. The end portions of the flanges 13 and 14 are offset from the planar face of the core, as indicated by the numerals 15 and 16 respectively, to form receiving shoulders for the means hereinafter described.

The core 10, which is of typical design, is shown more clearly in Fig. 2, and it is formed of juxtaposed sections consisting of water tube and fin ribbons 17 and 18. The water tube ribbons 17 are corrugated to form crests 19 and troughs 21, and further may contain one or more longitudinal depressions 22. These ribbons are each folded and a fin ribbon 18 is enclosed within the confines thereof to provide a section or unit 23. The sections are disposed in adjacent relation with the crests of one section disposed in the troughs of an adjacent section. The longitudinal depressions 22 of adjacent sections, by this arrangement, cooperate to form water passages 25, and they are open at the opposite ends or faces of the core for communication with the tanks 11 and 12. 35

Angle members 26 are provided to reinforce the corners of the core structure. Each member is formed with a vertical leg 27 having vertical raised surfaces 28 and depressed surfaces 29 which follow the transverse contour of the underlying ribbon 17. The horizontal leg 31 of the angle member is planar to engage the flat surface of the section extremities, and it is formed with apertures 32 registering with the underlying water passages 25.

The angle members, thus located, may be integrated with the core during the core soldering operation, when the front and rear faces of the core are successively immersed in molten solder to close the water ribbon passages and secure the fin and water ribbon elements together. During this operation, the solder by capillary action, will travel between all contacting surfaces of the angle members and ribbon portions covered thereby. On the vertical leg 55

27, for example, solder will travel along the crests 19 for the width of the covering member due to the conforming contour of the raised and depressed surfaces 28 and 29.

5 In cores of greater depth, such as herein shown, holes 34 may be provided in the vertical leg 27 adjacent to the corner of the member, to provide means for introducing additional solder to the central portions of the joint between the 10 horizontal leg 31 and the underlying section, to insure against the possibility of leakage.

Subsequent to the above described operation, the tanks are soldered in position to complete the assembly, wherein the receiving shoulders 15 and 15 16 of the tanks are proportioned to engage the horizontal legs 31 closely, and thus to provide efficient soldered joints therewith. It will be noted that the leg 29 does not extend along the core for its entire width, but is cut off so that 20 excess weight may be eliminated. In order to take care of the stress effects, the leg 29 may be from two to five times the length of the short leg 31 overlapping the outside water passage 17.

25 It will be understood that the described structure is exemplary of an application of the invention to one of the numerous known forms of radiators, and that it is not limited thereto, except as set forth in the following claims.

30 I claim:

1. A radiator comprising a core of the cellular type having water tanks secured to opposed ends thereof, one of said tanks having shouldered offset portions at each extremity spaced from the core, angle members disposed on the corners of the core and each having one leg received in the space between the core and the adjacent shouldered portion of the tank, and means securing the reinforcing means to the core and tank.

40 2. In a radiator comprising a core of the cellular type having upper and lower tanks secured

thereto, reinforcing means comprising an angle member disposed on a corner of the core and having one leg disposed between the core and tank, the remaining leg of the angle member being formed to conform to the transverse profile of the side wall of the core including offset formations on its opposite margins adapted to match the offset margins of the core, and means securing the angle member to the core and tank.

3. In a radiator comprising a core of the cellular type having upper and lower tanks secured thereto, reinforcing means comprising an angle member disposed on a corner of the core and having one leg disposed between the core and tank, the remaining leg of the angle member being formed to conform to the transverse profile of the side wall of the core, said remaining leg being formed with a plurality of holes adjacent the corner of the angle member for the introduction of solder to the underlying core, and means securing the angle member to the core and tank.

4. In a radiator comprising a core of the cellular type formed with spaced water passage openings at opposite ends thereof and upper and lower tanks secured to said opposite ends of the core, reinforcing means comprising angle members disposed on the corners of the core, each angle member having one leg received in the space between a shouldered portion and the adjacent portion of the tank and being also formed with openings registering with the underlying water passage openings, the remaining leg of the angle member being formed to conform to the transverse profile of the side wall of the core including offset formations on its opposite margins adapted to match the offset margins of the core, and means securing the angle member to the core and tank.

STANISLAUS PRZYBOROWSKI.
